T. E. SICKELS.
CONDENSER FOR STEAM ENGINES.Witnesses
H. King
A. M. Smith

Inventor
Theophilus E. Sickels

UNITED STATES PATENT OFFICE.

THEOPHILUS E. SICKELS, OF KENNETT SQUARE, PENNSYLVANIA.

IMPROVEMENT IN CONDENSING STEAM-ENGINES.

Specification forming part of Letters Patent No. 39,176, dated July 7, 1863.

To all whom it may concern:

Be it known that I, THEOPHILUS E. SICKELS, of Kennett Square, Chester county, and State of Pennsylvania, have invented a new and useful Improvement in Steam-Engines using Surface-Condensers; and I do hereby declare that the following is a full and accurate description of the same, reference being had to the accompanying drawing.

The nature of my invention consists in the combination of an air-pump and surface-condenser, with a blower to force a current of air through the condenser, for the purposes of condensing the steam and heating the air.

I do not confine myself to any particular form of air-pump, condenser, or blower, or to any particular arrangement of them, but in the accompanying drawing this invention is shown as applied to a street railroad car propelled by steam-power, which would be one of its most useful applications, as thereby there would be no escaping steam to frighten horses, nor would there be any necessity to carry the large amount of cold water to condense the steam used in the cylinders, as has been the custom heretofore in the engines used on street-railroads, known as "dummy-engines."

F is the car. H is an apartment in the car, containing the boiler, cylinder, air-pump, and machinery for the purpose of propelling the car and driving the blower and air-pump. I I is the surface-condenser, which may be of any approved form, into which the exhaust-steam passes through the pipe D. A is the air-pump, driven by the engine for pumping the uncon-

densed gases from the condenser through the pipe E. B is the blower, also driven by the engine, which, by its revolutions, drives a current of air through the condenser-tubes T T, discharging it at O O. C is the steam-cylinder, which is used to propel the car and drive the air pump A and blower B.

Instead of discharging the heated air into the atmosphere at O O, it may, if desirable, be conducted into the car, and thereby serve to warm the passengers in cold weather. The hot water resulting from condensed steam in the condenser will accumulate in the bottom of the condenser, and would be used as feed-water for the boiler. This invention may also be used to great advantage for the purpose of heating buildings, as the exhaust-steam in being condensed will heat the air passing through the tubes of the condenser, which may be conducted to the different apartments, whereby the heat remaining in the exhaust-steam will be utilized.

Having thus fully described the nature of my invention, what I claim as new, and desire to secure by Letters Patent, is—

The combination and arrangement, in a condensing steam-engine, of an air-pump and surface-condenser, with a blower to force a current of air through the condenser to effect the condensation of the steam and to heat the air, substantially as set forth.

THEOPHILUS E. SICKELS.
